UNITED STATES PATENT OFFICE.

JOHN KREHBIEL, OF HARRISHILL, NEW YORK.

PRINTING-PRESS.

SPECIFICATION forming part of Letters Patent No. 733,325, dated July 7, 1903.

Application filed August 26, 1899. Renewed November 10, 1902. Serial No. 130,815. (No model.)

To all whom it may concern:

Be it known that I, JOHN KREHBIEL, a citizen of the United States of America, residing at Harrishill, in the county of Erie and State 5 of New York, have invented certain new and useful Improvements in Printing-Presses, of which the following is a specification, reference being had therein to the accompanying drawings.

10 My invention relates to that class of platen printing-presses where the paper is taken from a continuous web or roll and in which a reciprocating type-bed is employed.

The invention has for its principal object to 15 produce a press for general job-work whereby a strip of paper may be cut from a roll of greater width, according to the size job required, and to provide means whereby the paper is intermittently fed across the platen 20 and spaced with great accuracy, whereby I am enabled to do card-printing and color-work requiring great accuracy.

The invention further consists in the construction and operation of the paper-feed roll, 25 comprising clamping-fingers adapted to clamp the edges of the paper to the surface of the roll during a part of its revolution, and a locking device adjacent to said roll whereby the paper is fed a certain predetermined distance across the platen and locked in position 30 while the impression is being made, thus insuring uniform spacing between the forms and a perfect register.

The invention further consists in the peculiarity construction, arrangement, and combination of the various parts, all as more fully hereinafter described, and shown in the accompanying drawings, in which—

Figure 1 is an elevation of the printing-40 press. Fig. 2 is an end elevation thereof. Fig. 3 is an enlarged vertical section on line $x-x$, Fig. 1. Fig. 4 is a vertical cross-section on line $y-y$, Fig. 3, looking to the right. Fig. 5 is a plan view of a portion of the press, 45 showing the longitudinal paper-cutter. Fig. 6 is an end elevation of the paper-feed roll, showing the operating and locking mechanism therefor. Fig. 7 is a vertical section through one of the pivoted wear-blocks. Fig. 50 8 is a horizontal section on line $z-z$, Fig. 1, showing the adjustable connection.

A is the base of the press, and B represents the four corner-uprights stationarily secured therein.

C is the drive-shaft, mounted in suitable 55 bearings on the base and provided at its ends with the fly-wheels D D' and the belt-wheel D².

E represents pinions mounted on the shaft C just inside the bearings, and F F are gears on the crank-shafts G G, meshing therewith. 60

H represents vertical side walls integrally formed with the base, extending up therefrom, having the end guides a integrally formed thereon, in which the hollow plunger I is adapted to travel, suitable brasses or rub- 65 irons a' being interposed between the plunger and corner-brackets.

I may and preferably do dispense with the end guides a and guide the plunger I on the uprights B by means of the pivoted wear-blocks b, adjustably secured to lateral extensions c, formed on the upper end of the plunger or type-bed, by means of the set-screw d, as shown in Fig. 7.

I' I' are pitman-rods mounted on the crank-shafts G G, their upper ends working in suitable 75 pockets formed in the plunger I.

J is a rotary inking-disk of well-known construction carried by the plunger I, and K is the type-bed, mounted on the top of said 80 plunger.

L represents bell-crank levers pivoted in the frame of the machine and having extensible spring-arms e secured to the upper ends thereof, to the ends of which are attached 85 the opposite ends of the inking-carriage M, and M' is a shaft connecting the free ends of said levers, upon which is mounted one end of the connecting-link N, having its opposite end pivotally secured to the reciprocating 90 plunger.

N' is a platen stationarily mounted on the standards B near their upper ends, and N² is a horizontal rod supported in guide-bearings formed on the side of the supporting-frame of the platen. e' is a rack-bar secured to one end of said rod and meshing with the pinion U', sleeved on the shaft of the paper-feed roll.

O³ is a vertical rod pivotally secured in the 100 base of the press and with its upper end engaging in the slotted bearing f, formed on the

rod N^2 , and f' represents a series of adjusting-holes in the rod O^3 .

O' are disks secured to one end of the crank-shafts G G , and O^2 is a curved arm 5 having one end pivotally connected to the disk O and the opposite end adjustably connected to the vertical rod O^3 by means of the connection shown in Fig. 8, in which q is a sleeve adjustably secured on the screw-threaded end portion of the arm O^2 by means of the nuts x x , and z is a pin on the sleeve projecting at right angles thereto and adapted to form a pivotal connection with the arm O^3 by being inserted in one of the holes f' in said rod, a suitable nut z' being provided to hold the parts together.

In the operation of the parts a reciprocating motion will be imparted to the horizontal rod N^2 , carrying the rack-bar e' , which 20 through the medium of the pinion U' operates the paper-feed roll, and as the amount of movement imparted to the rod O^3 can be readily adjusted, by means of the adjustable sleeve, on the arm O^2 the amount of paper 25 fed across the platen can be regulated with reasonable accuracy. However, for color and other fine work requiring the minutest regulation in the paper feed I provide a second regulator or centering device, which I will describe 30 in detail farther on.

P is a vertical rod pivotally secured near its upper end to the bracket P' on one of the uprights B and having a slot P^2 near its lower end, in which the pin P^3 on the disk O' is 35 adapted to travel and impart an oscillating motion to the rod P , said rod carrying at its upper end the locking-dog P^4 .

R is a paper-roll supported on the arms S , adjustably secured on the supporting-frame. 40 I may and preferably do arrange the arms S so that they may be adjusted laterally as well as vertically, thereby permitting the use of any width or diameter of roll within the capacity of the machine.

45 S' is a spring-pressed rotary cutter adjustably mounted on the transverse shaft g' , secured to brackets on the supporting-frame, a suitable spring h being sleeved on said shaft and adapted to hold the cutter in contact 50 with the roll to cut the paper.

U is the feed-roll, journaled on the shaft V' , supported in suitable bearings and carrying the pinion U' , which meshes with the rack-bar e' . U^2 is a flanged disk secured to said 55 pinion and having internal ratchet formed thereon, and U^3 is a flanged disk stationarily mounted on the shaft V' , having enlarged peripheral slots e^2 cut in its periphery, (preferably corresponding in number to the ratchet-teeth on the disk U^2 .) In these slots the adjusting and locking dog P^4 on the rod P is adapted to engage to finally adjust and lock the parts while the impression is being made.

It will thus be seen that the locking mechanism is operated directly from the crank-shaft with the fewest possible intermediate parts, and as the rack-bar and gear can be

adjusted to within one space on the disk the dog will do the final centering of the parts, thus insuring accurate spacing.

70 U^4 is a dog pivotally secured on the disk U^3 in operative relation with the ratchet-teeth on the disk U^2 , so that the feed-roll will be rotated in but one direction—that is, while the impression is being made the feed-roll is 75 locked in position and the rack-bar is drawn to the left without revolving the feed-roll.

V represents sleeves stationarily secured to the bearings in which the shaft V' revolves, and U is the feed-roll, mounted on 80 said shaft, having transverse slots l cut in its periphery to permit of adjusting the clamping-fingers for any width of paper.

V^2 is a disk having a hub portion m stationarily secured to the sleeve V by the set-screw n , and o is a cam formed on the hub of said disk, adapted to lift the clamping-fingers out of engagement with the paper during one-half of the revolution of the feed-roll.

90 W is a hollow disk or casing mounted on the sleeve V and hub m free to turn thereon and having a finger p engaging in the slot l , whereby it is rotated with the feed-roll.

Y represents clamping-fingers carried by 95 the roll and provided with the stem r , having the inclined lower faces s , adapted to travel on the cam-face o and be lifted out of contact with the paper thereby.

t represents coil-springs sleeved on the 100 stems of the clamping-fingers between the shoulders formed on the disks, one end being secured to said stem, while the other end presses against the inner wall of the disk W , thereby tending to hold the fingers against 105 the feed-roll and at right angles to the edge of the paper.

r' represents lugs formed on the stems of the clamping-fingers Y .

n' represents semicircular lugs or projections formed near the outer edge of the disk V^2 , against which the lugs r' on the clamping-fingers are adapted to strike in the operation of the feed-roll, thereby causing the 110 said fingers to be turned parallel with the 115 edge of the paper and out of contact therewith against the tension of the spring t during one half-revolution of the feed-roll. It will

thus be seen that as the clamping-fingers ride up the incline o they will be lifted out 120 of contact with the paper, and at the same time the lugs r' will strike the inclined face of the projection n' and cause the fingers to be turned parallel with the edge of the paper for nearly one half-revolution of the feed-roll, so that the paper is free to leave the feed-roll and pass to the folder or cutting device, as desired. As the fingers again leave the cam groove or projection n' the spring t will cause them to spring back to their normal position, and upon riding down the inclined face of the cam o the fingers will again 125 clamp the paper and draw it across the platen the desired distance. It will thus be seen 130

that with my construction of press I am enabled to use any width of paper that may be obtainable on the market, which is of especial advantage to the job-printer who carries but a limited supply of paper on hand. Further, with the construction of the combined spacing device and feed-roll I am enabled to obtain an accurate feed and the closest register possible, which is of especial advantage in color-printing when two forms are used side by side on one type-bed, first printing one color and then feeding the paper transversely to the next form and printing the second color.

15 What I claim as my invention is—

1. In an intermittent web-printing press, the combination with the reciprocating type-bed, of a feed-roll operating in unison with the type-bed to draw the paper across the platen, two sets of clamping-fingers at opposite ends of the roll, and means for imparting a combined radial and rotary movement to said fingers by the movement of the roll, to clamp the edges of the paper upon the roll 25 during a portion of its revolution and to release the same.

2. In an intermittent web-printing press the combination with the reciprocating type-bed of a feed-roll operating in unison with the type-bed to draw the paper across the platen of two sets of clamping-fingers at opposite ends of the roll and adapted to clamp the edges of the paper upon the roll, said clamping-fingers having shanks radially supported in guide-bearings on the roll, retracting-springs upon the shanks and cams stationarily secured within the roll and imparting a radial and rotary movement to the clamping-fingers in the movement of the roll.

35 3. In an intermittent web-printing press the combination with the reciprocating type-bed, of a feed-roll operating in unison with the type-bed to draw the paper across the platen, of two sets of radially-movable clamping-fingers at opposite ends of the roll, means for actuating said fingers by the movement of the roll to clamp the edges of the paper upon the roll during a portion of its revolution and to release the same by imparting a

40 slight radial movement and turning them upon their axis out of contact with the paper.

4. The combination with a reciprocating type-bed of the hollow feed-roll U, the shaft V' to which said roll is centrally connected, 45 the clamping-fingers Y mounted in longitudinal slots l in the ends of the roll, the heads W longitudinally adjustably secured within the ends of the roll and having radial guides for the shanks of the clamping-fingers, re-

50 tracting-springs t upon the shanks and cams o and n' stationarily secured within the open ends of the feed-roll and adapted to impart a radially-sliding and rotary movement to the clamping-fingers by the movement of the roll, the heads carrying the clamping-fingers and their actuating-cams being longitudinally adjustable within the roll.

5. In an intermittent web-printing press, the combination with a reciprocating type-bed of the feed-roll and its actuating mechanism for imparting a variable movement thereto in unison with the type-bed, a disk fast on the shaft of the feed-roll, provided with a series of radial slots enlarged at their outer ends formed in the periphery of said disk, a dog adapted to be thrown into and out of engagement with said slots and lock the roll in position and means independent of the operating mechanism for the feed-roll for positively operating said dog in timed relation therewith.

6. In an intermittent web-printing press, the combination with a reciprocating type-bed, of the feed-roll operating in unison therewith, a pinion mounted on the shaft of the feed-roll free to turn thereon and carrying a disk provided with ratchet-teeth, a rack-bar meshing with said pinion, means connected with the drive mechanism for imparting a variable movement to said rack-bar, a disk fast on the shaft of the feed-roll, ratchet-and-pawl connections between said disks to turn the drum in but one direction, a series of radial slots enlarged at their outer ends formed in the periphery of said disk, a dog adapted to be thrown into and out of engagement with said slots and lock the roll in position and means independent of the operating mechanism for the feed-roll for positively operating said dog in timed relation therewith.

7. The combination with a reciprocating type-bed, of a feed-roll operating in unison therewith, the pinion U' mounted on the shaft of the feed-roll free to turn thereon and carrying the disk U², the disk U³ stationarily secured on the shaft V' and a ratchet-and-pawl connection between said disks, the rack-bar e' meshing with said pinion, the rod O³ connected to said rack-bar having its lower end pivotally secured in the base of the machine, the curved arm O² pivotally secured to the disk O, and having its opposite end adjustably connected to the rod O³ near its middle.

8. In an intermittent web-printing press the combination with a supporting base or frame of the stationary platen secured thereto, the vertical reciprocating plunger carrying the type-bed and traveling in guides formed on the base, the pitmen I' pivoted in said plunger and actuated by the crank-shafts, the drive-shaft C supported in bearings between said crank-shafts, the pinions E meshing with the gears F thereon, and a transverse inking-carriage operated by and in unison with the plunger and having extensible arms e.

9. In a printing-press the combination with a stationary platen, a vertical reciprocating type-bed actuating means therefor, of means operating in conjunction with the drive mechanism to intermittently feed the paper across the platen, comprising a feed-roll having clamping-fingers operated by the movement

of the roll and a spacing and locking dog operated directly by the drive mechanism and in unison therewith, whereby said dog is adapted to take up the lost motion or slack 5 in the drive mechanism for the feed-roll.

10. In a printing-press, the combination with a stationary platen and a vertical reciprocating plunger carrying the type-bed and operating means therefor, vertical guides 10 having corner-brackets in which the plunger travels, an inking-carriage moving in unison with and operated by the movement of the plunger, means for intermittently drawing a 15 predetermined amount of paper across the platen, comprising a feed-roll having clamping-fingers in its opposite ends and a pinion U' loosely sleeved on the shaft thereof and meshing with the rack-bar e', the arm O³ connected to said rack-bar and having its lower end piv- 20 otally secured to the base of the press, the disks O O' mounted on the ends of the crank-shafts and the curved arm O² pivotally secured to one of said disks and adjustably connected to the arm O³, the lever P carrying the 25 dog P⁴ at its upper end operated directly from the drive mechanism adapted to take up the

lost motion in the drive mechanism of the feed-roll.

11. In a printing-press, the combination of a feed-roll recessed at both ends, heads axially 30 adjustably secured within the open ends of said roll, said heads carrying clamping-fingers and forming the means for adjusting the same to different widths of papers, said fingers being adapted to clamp the edges of the 35 paper upon the roll during a portion of its revolution and to release the same.

12. In a printing-press, the combination of an open-ended feed-roll, heads axially adjustably secured within said feed-roll and adapted 40 to rotate therewith, clamping-fingers carried by said heads, means for actuating said fingers by the movement of the roll, to clamp the edges of the paper upon the roll during a portion of its revolution and to release the 45 same.

In testimony whereof I affix my signature in presence of two witnesses.

JOHN KREHBIEL.
